UNITED STATES PATENT OFFICE.

HARRISON HORSFIELD, OF HALIFAX, ENGLAND, ASSIGNOR TO JOHN CROSSLEY & SONS, LIMITED, OF HALIFAX, ENGLAND.

MANUFACTURE OF CARPETS AND THE LIKE.

1,261,536.

Specification of Letters Patent.

Patented Apr. 2, 1918.

Application filed October 17, 1916. Serial No. 126,179.

To all whom it may concern:

Be it known that I, HARRISON HORSFIELD, a subject of the King of Great Britain, residing at 46 Woodside Crescent, Halifax, 5 Yorkshire, England, have invented new and useful Improvements in the Manufacture of Carpets and the like, of which the following is a specification.

This invention chiefly relates to the manufacture of carpets and like looped fabrics and has for its object to produce a novel pattern effect due to the employment of mottle or parti-colored warp threads (hereinafter for convenience of description referred to as 15 warp-yarns) twisted some in one direction and some in the opposite direction, without the employment of any pattern mechanism and without the printing or dyeing of the warp-yarns as in tapestry carpets.

20 Heretofore in the manufacture of woven fabrics it has been proposed to employ warps some of which are twisted in one direction and some in the opposite direction for the purpose of obtaining effects of light 25 and shade, and it has also been proposed to heighten the effect by employing colored yarns.

Also it has been proposed, and it is well known, to employ mottle or parti-colored 30 yarns, that is to say, yarns composed of two or more threads of different colors twisted together.

According to my invention these two methods are combined, that is to say, the 35 beam is made up partly of warp-yarns twisted or folded from left to right and partly of warp-yarns twisted or folded in the reverse direction, and each warp-yarn is advantageously composed of three threads, 40 these threads being of three different colors, or two of one color and one of another.

Whatever may be the arrangement, the general effect in the woven fabric, having the warp-yarns arranged as above described, is a series of irregular zig-zag lines 45 of color in the transverse direction of the fabric. If the oppositely twisted warp-yarns are placed alternately the result is that the zig-zags will be rather short and narrow 50 while the result of grouping several warp-yarns of the same direction of twist is that the lines of the zig-zags will be broad and long.

It is to be understood that all the warp- 55 yarns of a beam need not be of the same

character as regards coloring for example, certain of the warp-yarns might be composed of, say, two threads of light color and one of dark, while adjacent warp-yarns or groups of warp-yarns might have two 60 threads of dark color and one of light.

A carpet having a pattern upon it produced by jacquard mechanism may have the ground or filling patterned as described.

My invention will be readily understood 65 by reference to the accompanying drawing, in which:—

Figure 1 illustrates a looped carpet fabric in which the beam is composed of groups of oppositely twisted warp-yarns. 70

Fig. 2 is a similar view wherein the beam is composed of alternate oppositely twisted warp-yarns, and

Fig. 3 is a view of a piece of fabric having a jacquard pattern upon it and a filling or 75 ground composed of alternately oppositely twisted threads as shown in Fig. 2.

In all the above figures the zig-zag form of the pattern is most clearly seen by viewing the drawing in the direction of its 80 length in a plane nearly parallel with its surface.

In these figures *a a* indicate the usual foundation warp-threads, *b, b* color warp-yarns twisted from right to left, and *c, c* 85 color warp-yarns twisted from left to right. *d, d* are the weft threads for binding the color warp-yarns to the foundation warp-threads in a manner well known in the weaving of carpets. 90

The fabric illustrated in Fig. 1 has alternate groups of four warp-yarns twisted from left to right and from right to left, and each warp-yarn consists of three differently colored threads which are indicated in black, 95 white and hatch lines respectively.

The fabric illustrated in Fig. 2 is composed of alternate warp-yarns twisted in opposite directions, and each consisting of two threads of one color, indicated in white, 100 and one thread of another color, indicated in black.

With the latter arrangement it will be seen that the zig-zag lines of the pattern are much shorter than in the arrangement previously described and that instead of the three colors being uniformly distributed as in Fig. 1, one color predominates, it will be noticed, however, that the general effect is the same. 110

In both of the above examples the folded or twisted warp yarns can be run off a beam, common to them all, in a plain loom.

When manufacturing a fabric having a pattern *e* produced upon it by jacquard mechanism, as shown, for example, in Fig. 3, it will be obvious that the length of warp threads *a* required for the ground or filling will vary according to the character of the jacquard pattern, and in this case therefore the parti-colored warp threads must be run off creels or frames situated behind the jacquard as usual.

It is not necessary that the pattern of a fabric, woven in accordance with this invention, should be of the same character throughout, as, for instance, the coloring of the warp-yarns in the different groups may be varied, so that the fabric, while possessing the desired characteristic as to the pattern, will be composed of groups of warp-yarns of varying shade or color; and again, the central portion of a carpet or fabric may have a pattern produced as hereinbefore described, while the borders may be woven with any desired pattern in the ordinary manner; or the center of a width of fabric may be woven with any desired design or pattern, while the borders are provided with a pattern in accordance with my invention.

Copies of this patent may be obtained for five cents each, by addressing the "Commissioner of Patents, Washington, D. C."

Claims:

1. A looped woven fabric having a pattern produced by employing warp-yarns composed of a plurality of mottle or parti-colored threads, some of which warp-yarns are twisted in one direction, and the others in the opposite direction, substantially as described. 35

2. A looped woven fabric having a pattern produced by employing mottle or parti-colored warp-yarns in groups, the warp-yarns in one group being twisted to the right and those in adjacent groups to the left, substantially as described. 40

3. A looped woven fabric composed of mottle or parti-colored warp-yarns twisted alternately in opposite directions, substantially as described. 45

4. In a looped woven fabric having a pattern upon it produced by jacquard mechanism, a ground or filling composed of parti-colored warp-yarns some of which are twisted in one direction and the others in the opposite direction, substantially as described. 50
